UNITED STATES PATENT OFFICE.

SWENEY MUNSON, OF FOWLER, COLORADO.

GUARD-RAIL CLAMP.

1,027,212.

Specification of Letters Patent. Patented May 21, 1912.

Application filed June 7, 1911. Serial No. 631,727.

To all whom it may concern:

Be it known that I, SWENEY MUNSON, a citizen of the United States, and a resident of Fowler, in the county of Otero and State 5 of Colorado, have invented a new and Improved Guard-Rail Clamp, of which the following is a full, clear, and exact description.

The object of the invention is to provide a new and improved guard rail clamp, arranged to permit of conveniently placing it in position on a traffic rail and its guard rail, and to allow of fastening it in place without weakening the web of the traffic rail for the passage of bolts or other fastening devices.

For the purpose mentioned, use is made of a rail clamp, having a base for the traffic rail and guard rail to rest on, and an integral clamping arm extending from one end of the 20 clamp and engaging the outer side of the guard rail, a brace secured to the said clamp base and engaging the outer side of the traffic rail, a filler block fitting between the said rails, and transverse bolts for fastening the filler block to the guard rail.

A practical embodiment of the invention is represented in the accompanying drawings forming a part of this specification, in which similar characters of reference indicate corresponding parts in all the views.

Figure 1 is a plan view of the guard rail clamp as applied, parts being shown in section; Fig. 2 is a sectional side elevation of the same on the line 2—2 of Fig. 1; and Fig. 35 3 is a transverse section of the same on the line 3—3 of Fig. 1.

The bases of the traffic rail A and the guard rail B rest on the base member C' of a guard rail clamp C provided with an upwardly-extending arm C² fitting onto the outer side of the guard rail B, as plainly illustrated in Fig. 3. The base member C' of the guard rail clamp C is provided with a shoulder C³ fitting against the outer edge 45 of the base of the traffic rail A, so that when the guard rail clamp C is in position on the traffic rail A and the guard rail B then the said rails are held against lateral movement on the base member C' of the guard rail clamp C. On the end C⁴ of the guard rail clamp C is held a brace D fitting against the outer side of the web of the traffic rail A, against the outer side of the outer portion 50 of the head of the said rail, and onto the top of the base of the said rail A, as will be readily understood by reference to Fig. 3,

the said brace D being fastened by bolts E to the outer end C⁴ of the guard rail clamp C. The brace D is provided with a depending tapering pin D' passing through a correspondingly shaped opening C⁵ in the outer end C⁴ of the guard rail clamp C, and the lower end of the tapering pin D' is provided with an opening D² into which is driven a key F abutting against the under side of the 60 base member C' of the guard rail clamp C so as to securely fasten the brace D in place on the guard rail clamp in addition to the bolts E previously mentioned, and at the same time the taper of the pin D' forces the 70 brace D inward in firm contact with the outerside of the traffic rail A.

Between the traffic rail A and the guard rail B is placed a filler block G fitting against the opposite faces of the webs of the 75 rails A and B, against the under side of the inner portions of the rail heads and onto the top of the inner portions of the bases of the said rails, so that the rails A and B are held properly spaced apart. Transversely-extending bolts H pass through the filler block G and through bolt holes in the web of the guard rail B, and also through washers G' held against the outer face of the web of the guard rail B and fitting against the 85 under side of the outer portion of the guard rail head, and also onto the top portion of the base of the said guard rail B. The washers G' are arranged on opposite sides of the arm C² so that the filler block G is held 90 against lengthwise movement relative to the rails A and B.

On the top of the filler block G is secured a foot guard I of heavy sheet metal or other suitable material, and extending beyond the 95 filler block G a desired distance between the rails A and B, the end I' being turned downward, as indicated in Figs. 1 and 2, the foot guard serving to prevent the heels of switchmen or other persons from being caught between the rails A and B. A screw J or other fastening means serves to fasten the foot guard I in position on top of the filler block G.

Tie plates K extend under the bases of 105 the rails A and B and rest on top of the ties L, and each tie plate K is provided in the portions projecting beyond the bases of the rails A and B with apertures K', some of which are in register with notches B' 110 formed in the outer portion of the base of the guard rail B, and through the said

tie plate openings K' are driven spikes N into the ties L, and some of the spikes pass through corresponding notches B' to hold the tie plates in firm relation with the guard rail B and consequently with the traffic rail A.

From the foregoing it will be seen that by the arrangement described, the main rail A is not weakened by bolt holes for the passage of bolts used to secure the filler block G or other parts in place, and hence the original construction of the traffic rail is maintained. It will also be noticed that by the arrangement described the guard rail B is not liable to change its position relative to the traffic rail A, so that the guard rail properly serves its intended purpose.

Having thus described my invention, I claim as new and desire to secure by Letters 20 Patent:

1. In combination, a traffic rail, a guard rail, a guard rail clamp having a base for the said rails to rest on and a clamping arm engaging the outer side of the guard rail, a brace for engaging the outer side of the traffic rail, the said brace having a depending locking member extending through the clamp base, means for fastening the brace to the clamp base, a filler block fitting between the rails, and means for fastening the said filler block to the guard rail.

2. In combination, a traffic rail, a guard rail, a guard rail clamp having a base for the said rails to rest on and an integral clamping arm engaging the outer side of the guard rail, the said clamp base having a shoulder engaging the outer edge of the base of the traffic rail, a brace engaging the outer side of the traffic rail and having a depending locking pin extending through

the clamp base, a key engaging the said pin and resting against the under surface of the clamp base, a filler block fitting between the rails, and transverse bolts for fastening the said filler block and the web of the guard rail together at opposite sides of the clamping arm of the guard rail clamp.

3. In combination, a traffic rail, a guard rail, a guard rail clamp having a base for the said rails to rest on and an integral clamping arm engaging the outer side of the guard rail, a brace engaging the outer side of the traffic rail and having a depending tapering pin engaging a corresponding aperture in the rail clamp, bolts for fastening the said brace to the said clamp, and a filler block between the said rails.

4. In combination, a traffic rail, a guard rail, a guard rail clamp having a base for the said rails to rest on and an integral clamping arm engaging the outer side of the guard rail, a brace engaging the outer side of the traffic rail and having a depending tapering pin engaging a corresponding aperture in the rail clamp, bolts for fastening the said brace to the said clamp, a filler block between the said rails, washers fitting the outside of the guard rail on opposite sides of the said clamping arm, and transverse bolts fastening the said filler block, the web of the guard rail and the said washers together.

In testimony whereof I have signed my name to this specification in the presence of two subscribing witnesses.

SWENEY MUNSON.
